UNITED STATES PATENT OFFICE.

EMIL IBACH, OF PHILADELPHIA, PENNSYLVANIA, ASSIGNOR TO BUDD WHEEL CORPORATION, OF PHILADELPHIA, PENNSYLVANIA, A CORPORATION OF VIRGINIA.

PIERCING-PUNCH AND DIE.

1,338,082.

Specification of Letters Patent. Patented Apr. 27, 1920.

Application filed December 28, 1918. Serial No. 268,641.

To all whom it may concern:

Be it known that I, EMIL IBACH, a citizen of Germany, who have declared my intention to become a citizen of the United States, 5 residing at Philadelphia, in the county of Philadelphia and State of Pennsylvania, have invented certain new and useful Improvements in Piercing-Punches and Dies, of which I declare the following to be a 10 full, clear, and exact description.

The present invention relates to an improved punch press particularly adapted for punching holes in the rims of wire wheels, which, as is well known in certain types of 15 construction, are located at an angle to the base or channeled portion of the rim in order to receive the wire spokes at the proper angles to the plane of the wheel tread. It is to be understood, however, that 20 this invention in its broad concept is not limited to the manufacture of wire wheels, but has a wide range of use wherever a mechanism of the character may be adapted for punching holes in any kind of device or 25 articles.

The objects of the invention are to provide a novel arrangement for locating the articles in the punch press, for punching a hole therein preferably at an angle to a portion 30 of the article, as supported in the punch press, although not necessarily limited to the angular arrangement, and then upon a removal from the article of either the punching or die element of the press depending 35 on which is moved, to provide means for stripping or removing the article from the punch after the opening has been punched therein.

Further objects of the invention are to 40 provide a novel arrangement for punching the holes at an angle to the rim of a wire wheel construction, providing, in a simplified punch construction, a support adapted to hold the rim at an angle whereby when a 45 press is operated the opening punched therethrough will be made at an angle to the body portion of the rim of the wheel, a further feature being to facilitate punching the holes when adjacent the rim flanges.

In order to meet with commercial requirements, wire wheels must conform to the standard set by The Tire & Rim Association, and these standards require, that a space of a certain width must be left at the center 55 of the rim, which shall be uninterrupted,

except for the valve stem hole, and the spoke seats or depressions, must not encroach upon this space or "safety zone." In 60 clencher rims of certain sizes, it is difficult to punch the holes for the spokes, through the spoke seats, when these spoke seats are so located as to conform with the above 65 requirements, and one object of my invention is to provide an apparatus for punching such holes which will solve this difficulty.

Further objects of the invention are to provide a novel means *per se* for stripping the article from the punch after punching the opening in the article, to provide a novel 70 arrangement for insuring independently of the means just referred to, a proper return to normal position of the article support or stripper mechanism after one operation to properly position the mechanism for the 75 next punching operation.

Further objects of this invention relate to economies of manufacture and details of construction as will hereinafter appear from the detailed description to follow. I accomplish 80 the objects of my invention in one instance by the devices and means described in the following specification, but it is evident that the same may be varied widely without departing from the spirit and scope 85 of the invention as is pointed out in the appended claims. Structures constituting certain embodiments of my invention, one of which may be the preferred, are illustrated in the accompanying drawings forming 90 a part hereof, in which:

Figure I is an elevational view of one embodiment of the punching-press.

Fig. II is a sectional view taken on the line 2—2 of Fig. I, showing the normal 95 position of the operative parts of the mechanism.

Fig. III is a sectional view similar to Fig. II, showing the punching position of the operative parts of the mechanism. 100

Fig. IV is a sectional view taken on the line IV—IV of Fig. II.

Fig. V is a sectional view of a modification of the invention.

Referring to the drawings, it will be seen 105 that there is shown a support or stand 10 of the press or punching machine, having a horizontally extending upper arm 11 which receives the reciprocating press member 12. Although not essential to the invention, 110

preferably the die of the punching-press 13 is carried by the press 12 and is reciprocated while a punch 14 is made a stationary member and operated upon to cause the 5 punching operation. One suitable means for mounting the punch 14 consists in supporting the same in a horizontally extending horn 15 suitably positioned within the stand 10 of the machine in any desired manner, as 10 by that illustrated in the drawing, wherein a mandrel 16 extends in an opening 17 in the standard and suitable means are provided for preventing rotation of the horn 15. To this end the support 10 is provided 15 with a groove 18 within which fits a squared retaining member 19 secured to the horn 15 by means of the bolts 20, for example. The squared edges of the lock 19 fit within the groove 18 which has the parallel sides as 20 shown, in order to rigidly maintain the horn 15 in the standard of the press against rotation or movement. The punch 14 is adjustable adjacent the outer edge or portion of the horn 15 and any means for adjust- 25 ably supporting the punch in the horn 15 may be provided. The means illustrated herein consist in locating the same in an opening 26 in the horn 15, and providing the screw bolt 27 through the end of the horn 30 15 and adapted to engage the punch 14 and hold the same securely in position. It will thus be seen that the punch 14 is adjustably mounted in the punching press.

One form of support for the articles to 35 be operated upon and a mechanism for stripping the same from the punch after a punching operation has been performed, consists in providing a movable support 30, this support, in the particular punching machine de- 40 signed herein, being provided with an inclined base 31 adapted to receive the rim of the wheel.

The support 30 is provided with an opening 32 therethrough, through which the 45 punching point 14' of the punch freely extends, the support 30 being adapted to slide over the punch as will hereinafter appear. Between the support 30 and the horn 15 is located mechanism for returning the sup- 50 port to normal position and stripping the article off the punch after a punching operation has been performed. One suitable mechanism for performing this function consists in providing an arm 35 pivoted at 55 36 to a support 37 suitably secured as by the screw bolt 38 to the horn 15. The stripper 35 is provided with an opening 39 there- 60 through, adapted to receive a stop device secured in the horn 15 forming means to limit the return of the stripper 35 and support 30 to normal position. A suitable arrangement therefor consists in a bolt 40 screw threaded into the horn 15, as shown, the bolt 40 passing through the opening 39 in the stripper 35. The horn 15 is provided with a recess 41

adapted to receive a coil spring 42, which bears on one end against the bottom of the recess 41, and on the other end against the bottom of the stripper 35. The spring operates to return the support or stripper to 70 normal position and remove the article from the punch. By surrounding the spring 42 around the bolt 40 the arrangement maintains the spring 42 in position but it is evi- 75 dent, of course, that the spring may be located elsewhere in the device, as may be deemed expedient. Attention is further called to the fact that any means for nor- 80 mally maintaining the support 30 in its nor- 85 mal position may be substituted for the spring 42, such as for example, the modification of the invention illustrated in Fig. V, hereinafter described.

As the die 13 operated by suitable mecha- 90 nism of this machine, (not shown) is re- turned after a punching operation to a cer- 95 tain set position, this operation may be utilized, if desired, to additionally insure the returning of the support 30 to normal position and the stripping of the article off 99 the punch 14. Thus, I have shown in the drawings a strap 45 connected at 46 by the bolts 47, to the stripper arm 35; the strap 45 extending upwardly to a point adjacent the overhanging arm 11 of the standard. The press 12 may be provided, if desired, with an extension, such as the plate 48 rig- 100 idly secured by means of the bolt 49 to the lower surface of the press 12, the extension 48 being so located as to engage the strap 45 and insure the raising of the stripper 35 to proper normal position. The plate 48 is preferably provided with an adjustable stud 50 screw threaded into the end of the plate and held in adjusted position by the 105 nut 51. Thus the contact of the plate 48 through the stud 50 with the strap 45 may be properly adjusted with relation to the adjustable stop 40 and timed with the oper- 110 ation of the punch to insure the proper re- turn of the stripper 35 and support to nor- 115 mal position. It is to be understood that the additional means in the strap 45 and the projection 48 on the press for insuring the stripping of the article from the punch 14 and the return of the support 30 to nor- 120 mal position may be entirely omitted, if de- 125 sired, and the means such as the spring 42 entirely relied upon to perform this function. The strap 45 and the allied mechanism is, therefore, merely an extra precautionary feature which, however, may be of consider- able utility in the operation of the machine, particularly for quantity production and the punching of a large number of holes in a minimum amount of time.

The operation of the improved mechanism described will, it is believed, be readily understood. It will be seen that the rim of the wheel A with its clencher edge or flanges B 130

may be readily positioned on support 30 in an inclined location with the flanges B out of the way so as to insure the punching of an inclined hole therein even adjacent a flange. After the article has properly been positioned on support 30, the press is operated and upon a descent of the press member 12, die 13 engages the base of the rim A carrying the same, together with the support 10 30 and the stripper arm 35 downwardly, thus forcing the punch 14 through the base of the channeled rim A of the wheel. It is to be understood that the moving parts of my improved type of punching-press could 15 be readily reversed and the punch moved while the die remains stationary. It is further apparent that various other specific detailed construction of the several coöperating parts of the mechanism described could 20 readily be varied, as may be deemed desirable, expedient or necessary by any person skilled in the art, and the details described herein, while particularly coöperating in the arrangement shown, and particularly effect- 25 ive and efficient in operation, however, are not essential to the operation of the invention or a reduction to practice thereof in its broad concept.

In the modification of the invention illustrated in Fig. V it will be seen that instead of using the coiled spring 42, I have shown a rubber block 55, capable of being compressed and expanding, interposed between the movable member 35 and the horn 15. A 30 suitable arrangement for this structure consists in providing a recess 15' in the horn 15 extending any distance deemed necessary, and be made of any desired size, receives a rubber block 55 made of any char- 35 acter of rubber or other flexible material, adapted to be compressed as the press and punch die descend over the punch and force down the support 30, and the movable arm 35. Upon a return of the press away from 40 the punch, the block 55 immediately expands, returning the movable elements 35 with the support 30 thereon to normal position, and stripping the article, such as the wheel rim A off the punch 14.

45 It will be further noted that in the embodiment of my invention illustrated in Fig. V the auxiliary secondary means for insuring a return of the arm 35 and support 30 to normal position is not shown as certain embodiments of my invention may be made in which it is not deemed unnecessary to provide the extra return mechanism or stripper operating means shown in Figs. I and IV. It is also evident from the two 50 modifications of my invention disclosed herein that several other modifications and embodiments thereon may readily be made without departing from the scope and spirit of the invention, consisting in a novel, sim- 55 plified arrangement of punching element in

a punching press for facilitating the production of articles in large quantities under efficient production methods.

While I have described my invention in more or less detail and as being embodied in certain precise forms, I do not, therefore, desire or intend to be limited thereto, since as already stated, my invention contemplates broadly all proper changes as well as the omission of immaterial elements and the substitution and equivalents therefor, the making integral of certain parts shown herein as separate pieces, and other changes as circumstances may suggest or render expedient.

Having thus described my invention, what I desire to secure by Letters Patent of the United States and claim is:

1. In a machine of the class described, in combination, a die, a punch, a support extending between said die and punch for holding an article in an inclined position between said die and said punch, and means for causing a relative movement between said die and punch to force the punch through the article and form an opening therein at an angle to a plane portion thereof.

2. In a machine of the class described, the combination of a die, a punch, a support extending between said die and punch for holding an article in an inclined position between said die and said punch, means for causing a relative movement between said die and punch to force said punch through the article and form an opening there-through at an angle to a plane portion thereof, and means to strip the article from said punch after the completion of said punching operation.

3. In a machine of the class described the combination of a die, a punch, a support and stripper for holding an article in an inclined position between said die and said punch; means for causing a relative movement between said combined stripper and support and said punch, to force said punch through the article supported thereon, and means associated with said stripping support for returning the same to normal position after the completion of a punching operation to strip the article from the punch.

4. In a machine of the class described, the combination of a movable die, a stationary punch, a movable support for holding an article in an inclined position between said die and said punch, means to move said die toward said punch to move said support to force said article over said punch, and means to return said support and article to normal position after the operation of punching of a hole in the article has been performed.

5. In combination, a movable die, a

punch, a movable support for positioning an article over said punch, means to move said support in one direction, upon an operation of the machine to cause the die to force said article over said punch, and means to return said support to normal position after a punching operation has been performed.

6. In combination, a movable die, a stationary punch, a movable support for positioning an article over said punch, and between said die and said punch, means to move said support in one direction upon an operation of the machine to cause said die to force the article over said punch, means to return said support and article to normal position removed from said punch, and separate means coöperating between said die and said support for insuring a return of said support to normal position when said die is moved away from said punch.

7. In a machine of the class described, in combination, a movable press, a die carried thereby, a stationary horn and punch, a movable article support and stripper on said horn and arranged to be moved when said press is operated to cause said die to force an article over the punch and form an opening therethrough, and a spring interposed between said support and horn for returning the former to normal position.

8. In combination, a movable press, a die carried thereby, a stationary horn and punch, a movable article support and stripper carried by said horn and arranged to be moved when said press is operated to cause said die to force the article in the machine over said punch, and form an opening therethrough, a spring interposed between said horn and said support and stripper for returning the same to normal position, and means carried by said press engaging an element associated with said movable support and stripper for insuring a return of the latter mechanism to normal position.

9. In a device of the class described, in combination, a movable press, a die carried thereby, a stationary horn and a punch, a movable article supporting stripper supported on said horn and arranged to be moved when said press is operated to cause said die to force an article in the machine over said punch, and form an opening therein, a spring interposed between said horn and said support for returning said support to normal position, and a stop for limiting the return movement of said support and stripper.

10. In a machine of the character described, the combination of a movable press, a die carried thereby, a movable article support and stripper, supported in the machine and arranged to be moved when said press is operated to cause said die to force said article over said punch and form an open-

ing therethrough, means to return said support to normal position, an adjustable stop for limiting the operation of said means, and adjustable means carried by said press for coöperating with an element associated with said stripper to insure a return of said stripper and support against said stop.

11. In a machine of the character described, in combination, a die, a punch, a movable article support and stripper arranged to be moved when said press is operated to cause a relative movement between said die and punch to force an article located on said support over the punch and form an opening therethrough, a pivoted stripper arm coöperating with said support and moved thereby in one direction, and means acting on said stripper arm for returning the same and said support to normal position to remove the article from the punch after performance of the punching operation thereon.

12. In a machine of the character described, the combination of a punch, a die, an article support between said die and said punch, a pivoted arm coöperating with said support, for moving said support in one direction, an element secured to said member between the pivot thereof and said support adapted to extend in the line of movement between said die and said punch, and means for coöperating with said element to move said pivoted arm to normal position upon the operation of the machine in a manner set forth.

13. In a machine of the class described, the combination of a press, a die carried by said press, a horn supported from said machine, an article support and stripper movably carried by said horn, said support having an opening therethrough, a punch mounted on said horn and extending through said support.

14. In a machine of the character described, the combination of an operating punch and a die, means to support an article between the two, including an article support provided with an opening, said punch adapted to extend through said opening, means operative upon an operation of the machine to force said article and support over said punch, and form an opening in the article, and means to return said support to normal position.

15. In a machine of the class described, in combination, a die, a punch, a support for holding an article in an inclined position between said die and said support, said punch extending through said support, and means for causing a relative movement between said die and said punch to move said support over said punch and force the punch through the article and form an opening therein at an angle to a plane portion of said article.

16. In a punching machine of the character described, the combination of a supporting member, a reciprocating die carried thereby, a stationary punch supported from 5 a fixed part of the machine, a movable article support located over said punch, said support having an opening therethrough to receive said punch, means to move said article and support over said punch upon an 10 operation of said die, and means to return said article and support to normal position in timed relation to the removal of the die from the punch for the purposes set forth.
17. In a machine of the class described, 15 the combination of a reciprocating die, a stationary horn, an article support carried by said horn and extending between said horn and said die, said article support having an
- opening therethrough, and a punch mounted on said horn and extending through said opening. 20
18. In a machine of the class described, the combination of a die and punch, an article support having a surface inclined at an angle to the plane perpendicular to the common axis of the die and punch, said support having an opening therethrough and said punch extending through said opening, and means for causing a relative movement between said die and punch to force the 25 punch through the article and form an opening therein at an angle to the plane portion thereof. 30

In testimony whereof, I affix my signature.

EMIL IBACH.
